GUIDED MISSILE

Otho E. McCrackin, Overland, Mo., assignor to the United States of America as represented by the Secretary of the Navy

Filed May 4, 1949, Ser. No. 2,422

Term of patent 3½ years

(Cl. D71—1)

FIG. 1

FIG. 2

FIG. 3

Fig. 1 is a perspective view of the guided missile as it would appear when seen obliquely from above at the front;

Fig. 2 is a perspective view of the guided missile as it would appear when seen obliquely from above at the rear, and

Fig. 3 is a side elevation of the guided missile.

The characteristic features of my guided missile design are shown by means of full lines in the drawing and comprise aspects of the rear or tail end and superstructure assemblies, and the curvilinear confluence of the superstructure and wings with the missile fuselage.

What is claimed is:

The ornamental design for a guided missile, substantially as shown and described.
